UNITED STATES PATENT OFFICE.

PETER SJOSTROM, OF MAPLEWOOD, MASSACHUSETTS, ASSIGNOR TO VICTOR SHOE MACHINERY COMPANY, OF BOSTON, MASSACHUSETTS, A CORPORATION OF MASSACHUSETTS.

PRESSER-FOOT MECHANISM FOR SEWING-MACHINES.

Specification of Letters Patent.

Patented July 4, 1916.

1,190,199.

Original application filed February 17, 1915, Serial No. 9,465. Divided and this application filed March 27, 1915. Serial No. 17,943.

To all whom it may concern:

Be it known that I, PETER SJOSTROM, a subject of the King of Sweden, and a resident of Maplewood, in the county of Middlesex and State of Massachusetts, have invented certain new and useful Improvements in Presser-Foot Mechanisms for Sewing-Machines, of which the following is a specification.

10 This invention relates to presser foot mechanisms for machines for sewing heavy material such as leather, and particularly to that class of machines known as welt sewing machines, and is a division of an application filed by me Feb. 17, 1915, and numbered 9,465.

15 The object of the present invention is to provide a new and improved presser foot mechanism which will be automatically operated to accommodate the presser foot to various thicknesses of material while the presser foot is also adapted to be removed from the work when desired without affecting the automatic devices for actuating said 20 presser foot.

25 Another object of the invention is to provide said presser foot mechanism with means for automatically controlling the amount of thread drawn from the source of supply 30 whereby the required amount of thread for various thicknesses of material is always assured.

35 The invention consists of certain novel features of construction and arrangement of parts which will be fully understood by reference to the description of the drawings and to the claims hereinafter given.

40 Of the drawings: Figure 1 represents a side elevation of a machine embodying the principles of the present invention. Fig. 2 represents a sectional detail showing the opposite side of the presser foot mechanism. Fig. 3 represents a plan of the presser foot mechanism and the thread regulating devices. Fig. 4 represents a front elevation of the machine. Fig. 5 represents a left end elevation of the same, and Fig. 6 represents a vertical section of the same.

45 Similar characters designate like parts throughout the figures of the drawings.

50 In the drawings, 19 is a connector the lower end of which is connected to any well-known form of driving mechanism, while

the upper end is pivotally connected to a lever 20 loosely mounted upon a stud 21 non-revolvably mounted in a boss 22 formed upon the frame 23, the base 24 of which is adapted to be secured to any well-known form of support. The lever 20 is secured by means of the bolt 26 to the gear segment 27, the hub 28 of which is mounted upon the stud 21 about the axis of which it is adapted to be oscillated.

55 By means of the connector 19, oscillatory movement may be imparted to the gear segment 27, the lever 20 moving through an arc the ends of which are indicated by the dotted outlines *a* and *b* of the lever end. The teeth of the gear segment 27 mesh with the teeth of the gear 29 secured to a shaft 30 60 mounted in bearings in the frame 23, in which bearings said shaft is adapted to be oscillated by means of the gear segment 27.

65 The shaft 30 has loosely mounted thereon a disk member 31 having formed thereon radial shoulders 32-33 which are adapted to be engaged by a pin 34 extending laterally from the gear 29. This pin 34, during the oscillation of the gear 29, will impart movement to the disk 31 when contacting 70 with either of the shoulders 32-33, while permitting said disk to remain at a standstill at the beginning of the movement of said pin 34 in either direction, that is, while traveling from the shoulder 32 to the shoulder 33 or vice versa.

75 The disk 31 is provided with a cam projection 35 adapted to engage the truck 36 on a lever 37 pivoted at 38 to the frame 23, the opposite end of said lever 37 being provided with a bearing member 39 adapted to engage the awl carrier 40 when it is desired to feed the work. The awl carrier 40 is provided with the usual curved awl 41. The truck 36 is retained normally in contact with the cam 35 by the spring 37 which forces the front end of the lever 37 upwardly, this outward movement being limited by the stop pin 38.

80 The bearing member 39 consists of a screw 100 threaded to the end of the lever 37 and held in adjusted position by means of the clamping nut 42. The awl carrier 40 is mounted upon a pin 43 extending through ears formed upon the needle carrier 45 said pin being 105 prevented from rotating by the clamping

screw 46. The needle carrier 45 is provided with the usual curved barbed needle 47 and oscillates about the stud 47^x fixed in the frame 23. The needle carrier 45 is provided 5 with a radial arm 45^x to the end of which is pivoted one end of a connector 106^x the opposite end of which is pivoted at 105^x to the disk 105 secured to and oscillating with the driving shaft 30. It is obvious that the 10 oscillatory movement of the shaft 30 will be imparted, through the connector 106^x, to the needle carrier 45 and in turn to the awl carrier 40. This awl carrier 40 is normally separated from the needle carrier 45 by the 15 spring 48 being compressed when by the movement of the lever 37 the awl carrier 40 is moved toward the needle carrier 45 to feed the work.

For a detailed description of the work 20 feeding mechanism reference may be made to the application #9465 hereinbefore referred to. A stud 50 is mounted in the frame 23 which serves as a pivot for the presser foot carrier 58 having secured there- 25 to the presser foot 59.

The carrier 58 has an upward extension 30 formed thereon by which the presser foot may be lifted from the work. The carrier 58 also has a rearward extension 61 to which is secured a ratchet plate 62 having a plurality of ratchet teeth 63 formed thereon in an arc of a circle concentric with the pivot 64 of a pawl lever 65, the outer end of which has articulated thereto, at 66, a pawl 67 normally engaging the ratchet teeth 63. The 35 pawl 67 is preferably secured by means of a pin 69 to a lever 68, also pivoted at 66. The lever 68 has secured thereto one end of a spring 70, the opposite end of which is secured to a fixed pin 71, the tension of said 40 spring normally retaining the pawl 67 in engagement with the ratchet teeth 63. The forward end of the lever 68 is positioned within the forked end 72 of a hand lever 73 45 pivoted at 64 to the presser foot carrier 58, said pivot 64 consisting of a stud extending through the lever 73 and the presser foot carrier 58 and being threaded to the lever 65 all as shown in dotted lines in Fig. 3. The 50 lever 68 is also provided on its under side with a cam projection 74 adapted to be engaged at predetermined times by a cam projection 75, upon a cam disk 76 secured to the shaft 30, in order to disengage the pawl 67 from the ratchet teeth 63. The lever 65 is provided with a truck 77 adapted to be engaged by a cam 78 also mounted upon the shaft 30. The presser foot carrier 58 is also provided with a laterally extending arm 79 55 to which is secured one end of a spring 80 the opposite end of which is secured to a member 81 pivoted at 82 to the rear of the frame 23. The member 81 is also provided with a lateral cylindrical projection 83 extending over the lateral extension 79 which

extension is provided with an upwardly extending flange 84 provided with a perforation through which the thread T passes from the source of supply between the projection 83 and the upper surface of the extension 79, 70 then downwardly through a hole 85 in said extension and upwardly through another hole 86 therein over said projection 83 and downwardly through the hole 87 in said extension along the under face of said extension 79 to an eye 88 and then downwardly into the wax pot 89.

The thread T passes from the wax pot 89 to the work as fully described in the application hereinbefore mentioned, the slack in 80 the thread being controlled by the take up lever 98 pivoted at 101 and moved about said pivot by the connector 103 pivoted at one end at 102 to said take up while its opposite end is pivotally connected at 104 to 85 the disk 105. The shaft 30 extends beyond the left end of the machine and has adjustably secured thereto the arm 134 having a truck 135 at its outer end positioned in a cam groove 136 formed in a curved arm 137 90 of a lever 138. This lever 138 is pivoted at 139 and is provided with an oppositely extending arm 140 having formed on its outer end a gear segment 141. The teeth of this gear segment 141 engage the teeth of the 95 pinion 142 secured to the shaft 143 formed upon the shuttle drive 144. The shuttle 145 is mounted in a suitable fixed raceway 146 having pivoted thereto, at 147, a cap 148 which is adapted to be locked by a bolt 149. 100

The lever 81 is provided with a boss 151 to which is threaded an adjusting member 152, said member having threaded thereto a lock-nut 153 and also having a string 154 interposed between said nut and boss and surrounding the member 152. The nut 153 has a flat-sided contact with the inner face of the lever 65 as indicated in Fig. 3 of the drawings. This member 152 is for the purpose of regulating the distance the lock of 110 the stitch will be from the face of the work being operated upon, it being obvious that by adjusting the member 152 this lock may be located at any distance from the surface within reasonable limits. This is due to the 115 fact that all of the instrumentalities that assist in the formation of the stitch are operated by means of the oscillating driving shaft 30 and if the time of operation of the thread measuring device is varied relatively 120 to the operations of the other instrumentalities the location of the lock of the stitch will also be varied, this location depending on the amount of thread measured off. As the measurement of the thread is due to the 125 movement of the lever 81 about its pivot and as this movement is caused by the engagement of the shoulder 162 with the end of the member 152 it is obvious that by varying the position of the engaging end of the member 130

152 the operation of the thread measuring device will be correspondingly varied and as a consequence the location of the lock of the stitch from the surface of the work will be 5 similarly varied. When the member 152 has been adjusted for any particular work its position remains unchanged and at each oscillation of the cam shoulder 162 the same amount of movement will be imparted to 10 the lever 81.

As the operation of the machine continues, when there is any variation in the thickness of the material, the measurement of the thread will be automatically changed by the 15 variation in the position of the presser foot upon said material. This is due to the fact that the thread measurer 83 and the presser foot 59 are equidistant from the fulcrum 54 so that when the presser foot is lifted 20 a given distance to accommodate an increased thickness of material the lowering of the extension 79 will pull out more thread to accommodate this increased thickness of material. When for any reason it is desired 25 to pull out a quantity of thread T from the source of supply the operator may accomplish this by lifting the lever 81 and thereby drawing out the necessary length of thread which may then be pulled through the work 30 support 118. When the work is to be inserted, the operator seizes the handles 60—73 and by pressing them toward each other releases the pawl 67 from the teeth 35 63, thereby permitting the presser foot 59 to be lifted. When the work has been positioned, the presser foot 59 is moved into contact with the work and the handles 60—73 are released, thus permitting the pawl 67 to return into engagement with the teeth 63. 40 During the operation of the machine, the parts 58—65 and 68 are normally locked together, the cam 78 acting upon the roller 77 and retaining the presser foot 59 in gripping contact with the work. When the 45 feeding operation is about to occur, the gripping pressure upon the work will be released by the roller 77 entering the depression 160 in the cam 78 and the spring 70 causing the presser foot to be slightly 50 lifted from the work. The continued oscillation of the shaft 30 will cause the cam throw 161 to act upon the cam projection 74 and release the pawl 67 from the teeth 63 so that the presser foot 59 at the completion 55 of each feeding operation may accommodate itself to any variations in the thickness of the work when returning into contact therewith. At this time the projection 74 is in contact with the cam 75 and acts 60 as a fulcrum whereby the action of the spring 70 will pull down the rear end of the member 65 and lift the front end thereof, thus causing the presser foot to be moved into light contact with the work after which 65 the cam throw 161 being removed from contact with the projection 74 the pawl 67 will engage the teeth 63 and the continued reverse movement of the cam 78 will cause the presser foot to grip the work. It is obvious that the presser foot 59 is first brought into 70 light contact with the work and subsequently the gripping pressure thereon is effected by the cam 78 and that this gripping pressure is the same regardless of the thickness of the material. 75

The spring 70 is of considerable importance in the operation of the machine. Under normal conditions it retains the pawl 67 in engagement with the ratchet teeth 63 in whatever position the presser foot 59 may be. 80 When new work is to be inserted it is desirable that the presser foot 59 should be raised sufficiently to facilitate the positioning of the work upon the work support 118. To permit the lifting of the presser foot the 85 pawl 67 is disengaged from the teeth 63 by the movement of the lever 68 about its pivot 66 against the tension of said spring 70. This movement of the lever 68 is accomplished by the movement of the lever 73 90 about its pivot 64, the operator gripping the handles 60—73, and pressing them toward each other. As soon as the pawl 67 has been disengaged from the teeth 63 the presser foot carrier 58 may be freely moved about 95 its pivot 54 to lift the presser foot 59 while the work is being inserted, after which the operator releases the handles 60—73 and the spring 70 moves the presser foot 59 into light contact with the work after which the 100 spring 70 will immediately act to move the pawl 67 into engagement with the teeth 63 and prevent any accidental lifting of the presser foot. At this time the presser foot is only in light contact with the work but 105 when the cam 78 acts upon the roller 77 the carrier 58 is moved about its pivot 54 and the presser foot 59 is brought into gripping contact with the work. During this movement of the carrier 58 the pawl 67 is retained in contact with the teeth 63 by the spring 70 and if the ratchet plate 62 is moved the full length of a tooth 63 the spring 70 will cause the pawl 67 to be moved 110 into engagement with the next tooth. 115

When the feeding operation is about to occur the roller 77 will enter the depression 160 in the cam 78 and permit the spring 70 to pull down the rear arm of the carrier 58 and slightly lift the presser foot 59 from 120 the work. During this pulling down movement the pawl 67 will be held tightly enough against the teeth 63 by the spring 70 so that the carrier 58, lever 65, pawl 67, and lever 68 will act as if formed integral. At the 125 completion of the work feeding operation, the pawl 67 will be disengaged from the teeth 63 by the cam throw 161 acting upon the projection 74 of the lever 68 and moving it about its pivot 66 against the tension 130

of the spring 70. While the pawl 67 is disengaged from the teeth 63 and the projection 74 is on the highest part of the periphery of the cam 75 the spring 70 will pull down on the rear end of the lever 68, and as this is pivoted at 66 to the lever 65 it follows that the rear end of this lever 65 will also be moved downwardly and with the projection 74 as a fulcrum the front end will be moved 10 upwardly, causing the carrier 58 to be moved about its fulcrum 54 and the presser foot 59 brought into light contact with the work. The same action occurs when the operator releases the handles 60—73 after inserting 15 new work. Subsequently in the reverse movement of the cam 75 the throw 161 will pass beneath the projection 74 and the lever 68 will then be moved about its pivot 66 and the pawl 67 will become engaged with the teeth 63. After the pawl has 20 become engaged with the ratchet teeth continued reverse movement of the shaft 30 will cause the cam 78 to lift the roller 77 and move the carrier 58 about its fulcrum 54 with the presser foot 59 in gripping pressure 25 with the work. The gripping pressure on the work is always the same and is not applied until after the presser foot 59 has been brought into light contact with the work by means of the spring 70.

At every oscillation of the cam 35 the end 162 thereof will act upon the member 152 to move the lever 81 about the pivot 82, thereby moving the lateral projection 83 away from the extension 79 and measuring off the required amount of thread to form the stitch. This projection 83 is normally retained in contact with the upper face of the extension 79 and binds on the thread T, passing through the flange 84 to the opening 85. It is obvious that when this extension assumes a lower position, due to the increased thickness of the work, a greater amount of thread will be delivered inasmuch 40 as the limit of the upward movement of the lever 81 is always the same.

In the operation of the machine, the operator grasps the handles 60 and 73, moving them toward each other, thereby disengaging the pawl 67 from the teeth 63, thus permitting the presser foot 59 to be moved upwardly about the fulcrum 54 of the presser foot carrier. The work is then placed upon the work support 118 and the operator then releases the handles 60 and 73, permitting the spring 70 to move the presser foot 59 into contact with the upper face of the work, the pawl 67 at the same time being moved into engagement with the teeth 63, and locking the various members together. The distance of the lock of the stitch from the surface of the work may be determined accurately by the adjustment of the member 152. The gear segment 27 is 55 then oscillated in any well-known manner.

This oscillation of the segment 27 will impart oscillatory movement to the gear 29, and through this gear 29 to the main driving shaft 30. The pin 34 on the gear 29 will coact with the shoulders 32 and 33 of the cam member 35 and move this cam member 35 at the end of the movement of the pin 34 in either direction. The movement of the cam 35 will operate the lever 37 moving it about its pivot 38 and cause the bearing member 39 to force the awl carrier 40 toward the needle carrier 45, the awl 41 at this time being in the work and causing the work to be fed so that the puncture therein caused by the awl will be brought into the 75 plane of the needle 47, the awl 41 on completing its reverse movement being returned to its normal position by means of the spring 48. This reverse movement of the awl carrier does not occur until the point 80 of the awl is entirely free from the under face of the work. During every oscillation of the cam 35 the heel portion 162 thereof coacts with the adjustable member 152 and raises the lever 81 about its pivot 82 against 85 the tension of the spring 80. This lifting of the lever 81 will cause the lateral projection 83 thereon to be moved upwardly away from the extension 79 on the presser foot carrier 58, thus drawing from the source of 90 supply the necessary length of thread T for the formation of the next stitch. Normally the presser foot 59 is retained in gripping contact with the work by means of the cam 78 acting upon the roll 77 mounted 100 upon the lever 65 pivoted at one end to the presser foot carrier 58 and at the other to the pawl lever 68. When the feeding operation is about to take place the depression 160 in the cam 78 permits the roll 77 to be lowered and the presser foot 59 to be raised by means of the spring 70. The cam throw 161 immediately acts upon the pawl lever 68 to disengage it from the teeth 63 and the spring 70 then acts upon the lever 65 with the roll 105 77 as a fulcrum and causes the presser foot 110 to be brought into light contact with the upper surface of the work in its fed position. The return movement of the cams 75 and 78 will cause the pawl 67 to first 115 engage with the teeth 63 and then as the roll 77 moves from the depression 160 onto the higher portion of the cam 78 the presser foot 59 will be forced into gripping contact with the work.

It is obvious that by this construction means is provided whereby at every movement of the work the presser foot may adjust itself for variations in thickness of the material. It is obvious also that by the 125 presser foot 59 changing its position for varying thicknesses of material, the lateral extension 79 on the carrier 58 will be raised or lowered and consequently a lesser or greater amount of thread T will be drawn 130

from the source of supply, and to take care of these variations in the thickness of the material being acted upon.

It is believed that the operation and many advantages of this machine will be fully understood from the foregoing description.

Having thus described my invention, I claim:

1. In a machine of the class described, the combination of a stitch forming mechanism; a member for actuating said mechanism adapted to be oscillated during the formation of each stitch; means for oscillating said member; a work support; a presser foot mechanism; and a cam on said oscillating member for actuating said presser foot mechanism.

2. In a machine of the class described, the combination of an oscillating member; means for oscillating said member; a cam on said member; a work support; a presser foot provided with a rearward extension having ratchet teeth; a pivoted pawl engaging said teeth and controlled by said cam; and means pivoted to said presser foot extension for moving said pawl about its pivot.

3. In a machine of the class described, the combination of an oscillating member; means for oscillating said member; a cam on said member; a work support; a presser foot provided with a rearward extension having ratchet teeth; a lever pivoted thereto and controlled by said cam; a pawl pivoted to the free end thereof; resilient means for retaining said pawl in engagement with said teeth; and means for disengaging said pawl.

4. In a machine of the class described, the combination of an oscillating member; means for oscillating said member; a cam on said member; a work support; a presser foot provided with a rearward extension having ratchet teeth; a lever pivoted thereto and controlled by said cam; a pawl pivoted to the free end of said lever; resilient means for retaining said pawl in engagement with said teeth; and automatic means for disengaging said pawl at a predetermined time.

5. In a machine of the class described, the combination of a work support; a presser foot provided with a rearward extension having ratchet teeth; a cam controlled lever pivoted thereto; a pawl pivoted to the free end of said lever and having an arm provided with a cam engaging projection; resilient means for retaining said pawl in engagement with said teeth; and means for disengaging said pawl.

6. In a machine of the class described, the combination of a work support; a presser foot provided with a rearward extension having ratchet teeth; a cam controlled lever pivoted thereto; a pawl pivoted to the free end of said lever and having an arm pro-

vided with a cam engaging projection; resilient means for retaining said pawl in engagement with said teeth; and a cam adapted to engage said projection and disengage said pawl.

7. In a machine of the class described, the combination of a work support; a presser foot provided with a rearward extension having ratchet teeth; a cam controlled lever pivoted thereto; a pawl pivoted to the free end of said lever and having an arm provided with a cam engaging projection; resilient means for retaining said pawl in engagement with said teeth; a cam adapted to engage said projection and disengage said pawl; and a forked lever pivoted to said extension and adapted in its movement about said pivot to disengage said pawl.

8. In a machine of the class described, the combination of a work support; a pivoted presser foot having a rearward extension provided with a lateral arm with a plurality of thread holes therein; a coacting pivoted lever having a rounded projection; a spring interposed between said arm and lever to retain said projection in contact with the upper face of said arm; an oscillating member; and means on said oscillating member for moving said lever about its pivot to measure the thread passing around said lever projection and through the thread holes in said arm.

9. In a machine of the class described, the combination of a work support; a pivoted presser foot having a rearward extension provided with a lateral arm with a plurality of thread holes therein; a coacting pivoted lever having a rounded projection; an adjustable member on said lever; a spring interposed between said arm and lever to retain said projection in contact with the upper face of said arm; an oscillating member; and means on said oscillating member coacting with said adjustable member for moving said lever about its pivot to measure the thread passing around said lever projection and through the thread holes in said arm.

10. In a machine of the class described, the combination of a pivoted presser foot; a thread measuring device controlled thereby; and a single oscillating member for actuating both said presser foot and measuring device.

11. In a machine of the class described, the combination of a pivoted presser foot having a rearwardly extending arm with a plurality of thread holes therein; a pivoted lever having a lateral projection coacting with said arm over which the thread passes between two of said thread holes; and means for moving said lever relatively to said arm to measure the thread.

12. In a machine of the class described, the combination of a pivoted presser foot hav-

- ing a rearwardly extending arm with a plurality of thread holes therein; a pivoted lever having a lateral projection coacting with said arm over which the thread passes between two of said thread holes; and oscillating means for moving said lever relatively to said arm to measure the thread.
13. In a machine of the class described, the combination of a pivoted presser foot 10 having a rearward extension and a lateral arm with a plurality of thread holes; a pivoted lever having a lateral projection coacting with said arm over which the thread passes between two of said thread holes; 15 means for moving said lever relatively to said arm to measure the thread; a plurality of ratchet teeth on the free end of said extension; a pawl engaging therewith; and cam mechanism for controlling the engagement of said pawl.
14. In a machine of the class described, the combination of a pivoted presser foot having a rearward extension and a lateral arm with a plurality of thread holes; a pivoted lever having a lateral projection coacting with said arm over which the thread passes between two of said thread holes; means for moving said lever relatively to said arm to measure the thread; a plurality 25 of ratchet teeth on the free end of said extension; a pawl engaging therewith; cam mechanism for controlling the engagement of said pawl; and manually operated means for disengaging said pawl.
15. In a machine of the class described, the combination of an oscillating shaft; a gear secured to said shaft having a lateral projection; a member loosely mounted on said shaft adapted to be intermittently engaged by said projection; and a thread 30 measuring device operable by said loosely mounted member.
16. In a machine of the class described, the combination of an oscillating shaft; a gear secured to said shaft having a lateral projection; a member loosely mounted on said shaft adapted to be intermittently engaged by said projection; a thread measuring device; and an adjustable member 35 thereon adapted to be engaged by said loosely mounted member to operate said thread measuring device.
17. In a machine of the class described, the combination of a stitch forming mechanism; a driving shaft for actuating said mechanism adapted to be oscillated during the formation of each stitch; a work support; a presser foot; and means controlled by said 40 oscillating driving shaft for actuating said presser foot.
18. In a machine of the class described, the combination of a stitch forming mechanism; an oscillating driving shaft for actuating said mechanism adapted to be oscillated during the formation of each stitch; 45 a work support; a presser foot; and cam members on said oscillating driving shaft for actuating said presser foot.
19. In a machine of the class described, the combination of an oscillating driving 50 shaft; a work support; a pivoted presser foot having a rearward extension provided with a lateral arm with a plurality of thread holes therein; a coacting pivoted lever having a rounded projection; an adjustable member on said lever; a spring interposed between said arm and lever to retain said projection in contact with the upper face of said arm; and means on said oscillating driving shaft coacting with said adjustable 55 member for moving said lever about its pivot to measure the thread passing around said lever projection and through the thread holes in said arm to determine the locking position of the stitch in the work.
20. In a machine of the class described, the combination of an oscillating driving shaft; a work support; a pivoted presser foot having a rearward extension provided with a lateral arm with a plurality of thread 60 holes therein; a coacting pivoted lever having a rounded projection; an adjustable member on said lever; a spring interposed between said arm and lever to retain said projection in contact with the upper face of said arm; and means on said oscillating driving shaft coacting with said adjustable member for moving said lever about its pivot to measure the thread passing around 65 said lever projection and through the thread holes in said arm to determine the locking position of the stitch in the work.
21. In a machine of the class described, the combination of an oscillating member; a thread measuring device having a lateral lug thereon; a member threaded to said lug and adapted to be engaged by said oscillating member; a nonrevoluble nut on said threaded member; and a spring surrounding 70 said member between said nut and lug.
- Signed by me at Boston, Mass., this 17th day of March, 1915.

PETER SJOSTROM.
